UNITED STATES PATENT OFFICE.

JOHN ALLEN HEANY, OF WASHINGTON, DISTRICT OF COLUMBIA.

SELF-STARTING INTERNAL-COMBUSTION ENGINE.

1,174,717.

Specification of Letters Patent.

Patented Mar. 7, 1916.

Application filed April 29, 1912. Serial No. 693,890.

To all whom it may concern:

Be it known that I, JOHN ALLEN HEANY, a citizen of the United States, and a resident of Washington, in the District of Columbia, 5 have invented certain new and useful Improvements in Self-Starting Internal-Combustion Engines, of which the following is a full and clear specification, reference being had to the accompanying drawings, in 10 which—

Figure 1 is a side elevation broken away; Fig. 2 is a vertical section; and Fig. 3 is a view of the preferred form of means for controlling the movement of the valves shown 15 in Fig. 1.

The object of this invention is to so construct the starting mechanism that it shall be built into the engine proper, thereby doing away with the unsightliness, unreliability, lack of durability, and liability to derangement which are necessarily incident to those starting mechanisms which are mere attachments to an engine.

I have illustrated my invention as applied 25 to a well known type of engine (a four cycle twin-cylinder engine) but it will be understood that the invention is applicable, with modifications as to details, to other types of engines.

30 This invention has special relation to the type of self-starting engine covered by my copending application, Serial No. 688,634.

In the drawings, *a* designates the usual working pistons, *b* the working cylinders, *c* 35 the pitmen connecting the pistons to the main crank-shaft *d*, all constructed in substantially the usual manner. Each piston is extended toward the crank-shaft and provided with a supplemental piston *e* larger 40 in diameter than the main piston and working in a supplemental cylinder *f* formed as a continuation of the main cylinder.

The stroke of the pistons are so adjusted 45 that when the supplemental piston is at the upper extremity of its stroke there is a clearance *g* between the piston and the upper end or head of the supplemental cylinder, and communicating with this clearance space is a port *h*. Connecting all of these 50 ports to an air storage tank *i* is a pipe *j*, and controlling each port is an outwardly opening check valve *k*, normally pressed to its seat by a spring *l* and having a stem *m* which depends into the crank casing *n* of 55 the engine. The lower end of this stem is provided with an antifriction ball *o* which

is adapted to bear either upon the face of the cam *p* or the cylindrical face *q* of a sleeve carrying said cam. The cam sleeve *q* is affixed to a cam shaft *r* which is adapted 60 to be rotated by gears *s* or other suitable means from the crank shaft of the engine. This cam shaft *r* is adapted to be shifted endwise by any suitable mechanism, preferably by the means shown, which consists 65 of a gear *t* affixed to the cam shaft and provided with annular teeth, a gear *u* meshing therewith and affixed to a short shaft extending out through the crank casing and provided with another gear *v*. Meshing 70 with the gear *v* is a rack *w* carried by a rod *x* which may be adjusted back and forth by any suitable means, preferably by the lever and segment device shown in Fig. 3.

Attached to the cam-sleeve *q* is an additional pair of cams *y* and *z* which are separated from each other by a suitable space. Adapted to bear on the annular surface of the sleeve between these two cams or upon either of the cams, according to the adjustment of the cam shaft, is an antifriction ball *a'* carried at the lower end of a stem *b'* whose upper end is attached to a check valve *c'* which is normally seated by means of a coil spring *d'* in a valve chamber *e'*. Above 80 this valve *c'* the valve chamber *e'* is connected by a lateral port *f'* to the engine port *h* at a point below the check valve *k*. The valve chamber *e'* at a point underneath the valve *c'* is connected to the atmosphere 85 through the medium of a pipe *g'* and a silencer *h'*. The engine shown is a four cylinder type and the pistons operate in pairs. There is provided for each cylinder 90 a pair of the valves *k* and *c'* and a set of cams *p*, *y* and *z*. The pipe *g'* connects all the valve chambers *e'* to the silencer, and the pipe *j* connects all four of the engine 95 ports with the pressure tank *i*.

At a suitable point in the pipe *j* is arranged a check valve *i* which opens inwardly with respect to the air tank, being held to its seat by tank pressure and by a suitable coil spring *j'*. This valve is provided with a rod *k'* by which it may be 100 manually forced open and held open against tank pressure.

While the engine is running on its own power, the cam shaft is adjusted to the position shown in Fig. 1, in which position the balls *o* and *a'* rest on the cylindrical surface of the cam sleeve so that the cams will 110

not operate the valve but the valves will be nevertheless free to rise and fall in the manner of automatic check valves. While running in this manner, the supplemental pistons serve to pump air into the tank *i* and when the maximum pressure is reached the pumping action ceases automatically. This operation is as follows: Upon the downward stroke of each pair of supplemental pistons air will be drawn in through the silencer pipe *g'*, past the valve *c'* and in through the port *h*, the valve *k'* remaining closed. Upon the upstroke the air thus drawn in will be forced out past the valves *k* and on through pipe *j* past valve *i* and into the tank, the valve *i* and the valves *k* operating in the manner of automatic check valves. The pumping operation ceases as soon as the pressure in the tank is brought up to the degree determined upon in building the engine, this degree of pressure being dependent on the capacity of the supplemental cylinders and the amount of clearance *g* arranged for at the upper ends of the supplemental cylinders. As soon as the maximum pressure is obtained and the pumping into the tank ceases, then the air entrapped in each one of the supplemental cylinders at every stroke of its piston will be alternately compressed to tank pressure and then expanded to atmospheric pressure, thus providing for an ideal cushioning effect in each supplemental cylinder. If desired, in this pumping operation, the cam shaft may be adjusted to bring the cams *y* into alinement with the stems of the valves *c'* so that these valves shall be positively opened and held open during the suction strokes of the pistons.

When it is desired to start the engine through the medium of the pressure in the tank, the operator simply presses his foot upon the stem *k'* and opens the valve *i*, having previously shifted the cam shaft to bring the cams *p* and *z* into operation. This shifting of the cams serves to open and hold open two of the main check valves *k*, the cams being so arranged that they will open the valves *k* of those two supplemental pistons which happen to be at the upper ends of their stroke, ready for a working or down stroke. The cams *z* are so placed on the shaft that this same endwise movement of the cam shaft opens and holds open the two valves *c'* of those cylinders wherein the supplemental pistons are at the bottoms of their stroke or ready to ascend to expel the air in the cylinders into the atmosphere. It will thus be observed that while one pair of supplemental cylinders is taking air from the tank the other pair is ascending and expelling the air in the cylinders out past the previously opened valve *c'*, and this operation continues until the engine is working under its own power, after which the opera-

tor releases valve *i* and allows the same to close and then shifts the cam shaft to neutral position.

Having thus described my invention, what I claim as new and desire to secure by Letters Patent, is

1. In combination with a multiple cylinder explosive engine embodying supplemental cylinders and supplemental pistons connected to the work cylinders and pistons, and operated in unison therewith, a combined inlet and outlet port entering one end of each supplemental cylinder, a pair of check valves controlling each of these ports, means operated by the engine for opening these valves at predetermined times, means for shifting the valve opening means to convert the apparatus into a pump or into a starter for the engine, and an air storage tank connected to all of said ports. 75

2. In combination with a multiple-cylinder explosive engine, having air compressing means associated with each cylinder, of an air reservoir, a check valve opening toward said reservoir and controlling communication between the reservoir and the compressor, a second check valve opening toward the compressor and controlling communication between the compressor and the atmosphere, means operated by the engine 80 for opening these valves at predetermined times, and means for shifting the valve-opening means to convert the apparatus into a pump or into a starter for the engine. 85

3. In combination with a multiple cylinder explosive-engine having air-compressing means associated with each cylinder, of an air reservoir, a check valve opening toward said reservoir and controlling communication between the reservoir and the compressor, a second check valve opening toward the compressor and controlling communication between the compressor and the atmosphere, the lower end of each valve stem adapted to be engaged by a cam member operated by the engine for opening and closing these valves at predetermined times, and means for shifting the valve-opening means to convert the apparatus into a pump or into a starter for the engine. 100

4. In combination with a multiple cylinder explosive-engine having air-compressing means associated with each cylinder, of an air reservoir, a check valve opening toward said reservoir and controlling communication between the reservoir and the compressor, a second check valve opening toward the compressor and controlling communication between the compressor and the atmosphere, a rotating shaft associated with said check valves operated by the engine, cam members on said shaft adjacent the valve stems, said cam members adapted to engage the valve stems upon the longitudinal movement of said shaft for opening and closing 110

115

130

said valves at predetermined times, and means for shifting the valve-operating shaft for converting the apparatus into a pump or into a starter for the engine.

5. In combination with a multiple cylinder explosive-engine having air-compressing means associated with each cylinder, of an air reservoir, a check valve opening toward said reservoir and controlling communication between the reservoir and the compressor, a second check valve opening toward the compressor and controlling communication between the compressor and the atmosphere, the lower end of each valve stem adapted to be
- 10

engaged by a cam member carried by a rotating shaft operated by the engine for opening and closing these valves at predetermined times, and means for shifting the valve-opening means to convert the apparatus into a pump or into a starter for the engine.

In testimony whereof I hereunto affix my signature in the presence of two witnesses.

JOHN ALLEN HEANY.
